UNITED STATES PATENT OFFICE

2,631,528

MACHINE FOR PRINTING ERECTED
CARTONSWayne A. Wood, Kalamazoo, Mich., assignor to
Sutherland Paper Company, Kalamazoo, Mich.

Application August 29, 1949, Serial No. 112,953

4 Claims. (Cl. 101—44)

1

This invention relates to improvements in machines for printing erected cartons.

The main objects of this invention are:

First, to provide a machine for printing erected cartons which may be used in connection with a machine for erecting cartons to indicate contents, dating or the like as they are conveyed from the erecting machine.

Second, to provide a machine having these advantages which is simple and compact and enables the rapid changing of type for printing the desired indicia on a carton to indicate its contents.

Third, to provide a structure having these advantages which is automatic in its operation, all that is required of the operator is the changing of type as desired and adjustment of the type holder and inking pad for particular type used.

Objects relating to details and economies of the invention will appear from the description to follow. The invention is pointed out in the claims.

A preferred embodiment of the invention is illustrated in the accompanying drawings, in which:

Fig. 1 is a fragmentary view partially in vertical section on a line corresponding to line 1—1 of Fig. 2 with the parts in actuated position.

Fig. 2 is a fragmentary plan view with the type holder or printing element and platen in actuated position.

Fig. 3 is an enlarged fragmentary sectional view with the type holder or printing element and platen shown in retracted position by full lines and in actuated position by dotted lines.

Fig. 4 is an enlarged fragmentary view mainly in vertical section showing details of the type holder and the relation thereof to the platen with the parts in actuated position.

Fig. 5 is a fragmentary view partially in section on a line corresponding to the broken line 5—5 of Fig. 3 showing details of the mounting for the inking pad.

Fig. 6 is a perspective view of one of the printed cartons.

The embodiment of my invention illustrated comprises a suitable frame designated generally by the numeral 1. The conveyor, only portions of which are illustrated, comprises way members 2—2 disposed in spaced relation to provide a longitudinal slot 3. The way is provided with a rear side member 4 and front side member 5, the front side member having an opening 6 therein. In the embodiment illustrated the way and side members are formed of angle members facing inwardly and upwardly. The cartons designated generally by the numeral 7 are translated along the conveyor by means of flights 8 carried by the chain 9, the operative reach of which is supported by the bar 10. The details of the conveyor form no part of my present in-

2

vention and are therefore not further illustrated.

The embodiment of my invention illustrated is adapted for use in connection with a carton erecting machine, not illustrated, which erects the cartons to the position shown in Fig. 6 with the cover open and delivers the cartons to the conveyor which is driven with a step by step movement. This driving means is not illustrated but a suitable step by step movement may be provided by an interposition of a Geneva gear in the driving connections.

The contents of the cartons may vary, for example the pies in a day's run or production may have several kinds of fillers and the cartons cannot practically be previously printed to indicate such fillers. The same is true as to the character of cakes and other goods that may be packaged. To meet this condition I provide a type holder or printing element 11 adapted to receive a printing block 12. The holder 11 is pivotally mounted at 13 on the swinging end of the arm 14 which is pivotally mounted at 15 and provided with a lateral extension 16 to which the link 17 is pivotally connected.

25 The link 17 is pivotally connected to the rocker arm 18 which is in turn pivoted at 19 and provided with a roller follower 20 coacting with the cam 21 on the driving shaft 22. The driving means for this shaft are not illustrated. The conveyor is preferably driven from this same shaft. The arm 14 carries a threaded stop 23 with which the type holder coacts when the type holder is in printing position as shown in Fig. 4. The coil spring 24 is connected to the type holder below its pivot and acts to bias the type holder against this stop and also against the cam 25 which is positioned to engage the holder when it is in retracted position to present the type to the inking pad 26. The holder is provided with a cam portion 27 coacting with the cam 25. With this arrangement as the type holder is carried rearwardly by the supporting arm 14 it is brought into engagement with the cam 25 which tilts or swings it upwardly against the tension of the spring 24 and into engagement with the inking pad. As the arm swings forwardly the spring 24 swings the holder against the stop 23 to printing position.

50 The pad 26 is desirably cylindrical as illustrated and is mounted on a spindle 28 for rotative adjustment thereon, being secured in its adjusted positions by means of the thumbscrew 29. The spindle has an eccentric portion 30 engaged in the supporting bracket 31 which is split and provided with a clamping screw 32 for securing the spindle in its adjusted position. With this arrangement the inking pad may be adjusted to properly coact with the particular type mounted in the holder and to present all the surface 55 thereof.

To support the wall of the carton while being printed I provide the platen 33 carried by the angled arm 34 pivoted at 35 on the bracket 31 and with its angled portion projecting downwardly and offset at 36, the platen being mounted on the offset which permits the platen being swung into and out of the carton as shown by full and dotted lines in Fig. 3. The platen carrying arm 34 is connected by the link 37 to the rocker arm 38 pivoted at 39 and provided with a cam follower 40 coacting with the cam 41 on the shaft 22. The cams 21 and 41 are designed to simultaneously actuate the platen and the type holder to printing position. The single spring 42 connecting the rocker arms 18 and 38 urges their followers against their actuating cams.

The embodiment of my invention illustrated is a highly practical commercial embodiment and as stated is designed to be used in connection with a box setting up machine.

I have not attempted to illustrate and describe other embodiments or adaptations of my invention as it is believed that this disclosure will enable those skilled in the art to embody or adapt my invention as may be desired.

Having thus described my invention, what I claim as new and desire to secure by Letters Patent is:

1. The combination with a conveyor comprising a slideway provided with side members, the front side member having an opening therein, means for translating cartons along the way to successively position the cartons opposite said opening, a type holder, an arm having a fixed pivotal mounting at the front of said slideway and swingable in a plane normal to said opening and on the swinging end of which said type holder is pivotally mounted, an adjustable stop carried by the inner side of said arm relative to said slideway to coact with said type holder, a spring acting to bias said type holder towards said stop, an inking pad positioned in radially spaced relation to the swinging end of said arm, a fixed cam positioned to engage said type holder on the retracting stroke of said holder supporting arm whereby the holder is swung outwardly of the arm and the type carried by the holder is presented to the inking pad, a platen, a swingably mounted supporting arm for said platen pivoted in a transverse plane alongside of said slideway and having a hooked end on which said platen is carried and adapted to position the platen on the inner side of the wall of a carton in opposition to the said opening in the conveyor side member, the type holder being positioned to present type through said opening in opposition to the platen, and means for actuating said type holder and platen arms in synchronism.

2. The combination with a conveyor comprising a slideway provided with side members, the front side member having an opening therein, means for translating cartons along the way to successively position the cartons opposite said opening, a type holder, an arm having a fixed pivotal mounting at the front of said slideway and swingable in a plane normal to said opening and on the swinging end of which said type holder is pivotally mounted, a spring acting to bias said type holder towards the inner side of said stop relative to said slideway, an inking pad positioned in radially spaced relation to the swinging end of said arm, a fixed cam positioned to engage said type holder on the retracting stroke of said

holder supporting arm whereby the holder is swung outwardly of the arm and the type carried by the holder is presented to the inking pad, a platen, a swingably mounted supporting arm for said platen pivoted in a transverse plane alongside of said slideway and having a hooked end on which said platen is carried and adapted to position the platen on the inner side of the wall of a carton in opposition to the said opening in the conveyor side member, the type holder being positioned to present type through said opening in opposition to the platen, and means for actuating said type holder and platen arms in synchronism.

3. The combination with a conveyor comprising a slideway provided with side members, the front side member having an opening therein, means for translating cartons along the way to successively position the cartons opposite said opening, a type holder, an arm having a fixed pivotal mounting at the front of said slideway and swingable in a plane normal to said opening and on the swinging end of which said type holder is pivotally mounted, an adjustable stop carried by said arm to coact with said type holder, a spring acting to bias said type holder towards said stop, an inking pad positioned in radially spaced relation to the swinging end of said arm, a fixed cam positioned to engage said type holder on the retracting stroke of said holder supporting arm whereby the holder is swung outwardly of the arm and the type carried by the holder is presented to the inking pad.

4. The combination of a slideway adapted to have cartons translated therealong, a type holder, an arm having a fixed pivotal mounting at the front of said slideway and swingable in a plane normal thereto and on which said type holder is pivotally mounted to present type carried thereby to a side of said cartons, a spring acting to bias said type holder towards said arm, an inking pad positioned in radially spaced relation to the swinging end of said arm, a fixed cam positioned to engage said type holder on the retracting stroke of said holder supporting arm whereby the holder is swung outwardly of the arm and the type carried by the holder is presented to the inking pad, a platen, an angled supporting arm pivoted in a transverse plane alongside of said slideway and terminating in a forwardly offset portion at its swinging end to which said platen is secured to facilitate the platen entering an open carton and engaging the inside of the front wall thereof in opposition to the type holder, and means for actuating said type holder and platen arms in synchronism.
